UNITED STATES PATENT OFFICE.

HENRY L. DOHERTY, OF NEW YORK, N. Y.

METHOD OF HEATING COKE-OVENs.

1,150,840.

Specification of Letters Patent. Patented Aug. 17, 1915.

Application filed January 17, 1911, Serial No. 603,090. Renewed February 18, 1915. Serial No. 9,182.

To all whom it may concern:

Be it known that I, HENRY L. DOHERTY, a citizen of the United States, and a resident of New York city, in the county of New York and State of New York, have invented certain new and useful Improvements in Methods of Heating Coke-Ovens, of which the following is a specification.

This invention relates to a method of heating coke ovens, and particularly to a process of heating coke ovens and such like by means of producer gas generated in a gas producer functionally connected with the coke oven.

15 The object of my invention is to furnish an improvement in the art of heating coke ovens and the like whereby the whole of the gas generated in the carbonization of the coal may be saved and an inferior grade of 20 coal used in heating the oven, and also the maximum recuperation of heat, uniformity and efficiency of heating secured.

To this end my invention consists in heating the oven by producer gas generated in a 25 gas producer appurtenant to the oven, the combustion flues being arranged in parallel, the air, both for supporting combustion in the gas producer and the combustion of the producer gas, being preheated in a recuperator by the sensible heat carried out of the 30 combustion flues by the waste products of combustion, the air being passed through the recuperator usually under comparatively low pressure, and discharged into the respective 35 combustion chambers through nozzles, whereby, in the case of the gas producer, a current of flue gas is induced and passed into the fuel bed with the air current, and, in the case of the combustion flues of the 40 oven, a current of producer gas is induced into each flue and burned therein by the air.

In the accompanying drawings I have shown a form of apparatus suitable for applying my invention.

45 Figure 1 is a vertical longitudinal section through the apparatus on the line E, E¹, E², E³, E⁴, E⁵, E⁶, E⁷ of Fig. 2 through the gas producer, the producer gas and air recuperators and the combustion flues of one side of 50 the oven setting. Fig. 2 is a vertical cross-section of the same half of the oven setting on the line A, A¹, A², A³, A⁴, A⁵, A⁶, A⁷ of Fig. 1. Fig. 3 is a cross-section of the other half of the oven setting on the line A, B, B¹, B² of Fig. 1. Fig. 4 is a vertical cross-section 55 of the air recuperator on the same side

of the oven setting as the section of Fig. 3 (but looking in the opposite direction) on the line C, C¹, C², C³ of Fig. 1. Fig. 5 is a vertical cross-section of the same side of the oven setting as that of Fig. 2 (but looking in the opposite direction) on the line D, D¹, D², D³ of Fig. 1. Fig. 6 is a horizontal cross-section of one side of the setting on the line E, F of Fig. 1. Fig. 7 is a similar section of the other half of the setting on the line G, H of Fig. 1.

1, is the carbonizing chamber or coke-oven proper. 2 the gas producer, 3 the producer gas recuperator, 4 is the air recuperator, 5¹, 5², 5³, 5⁴, 5⁵, 5⁶, the combustion flues of one side of the oven setting, 6¹, 6², 6³, 6⁴, 6⁵, 6⁶, the combustion flues of the other side of the setting. 7 is the air blower.

The method of operation is as follows: A 75 comparatively deep layer of ashes having been laid on the grate, fuel is charged thereon and suitable kindling above this. The blower 7 is now started, air passing through the air pipe 8 to the air inlet-passages 9, 9' 80 in the front wall of the recuperator 4. Thence it enters the flues 10, 10', from whence it is distributed to the vertical flues 11, 11' of the respective air recuperators 4, 4'. On starting operations the dampers 12, 12' are closed, 85 which may be done by inserting a suitable rod through the hand-holes 13, 13'.

The air recuperators 4 and 4' are constructed as follows: The horizontal flues 14 are supported by a plurality of transverse 90 walls, 28, built up of specially-shaped tiles 29 and 30. The walls 28 rest upon the key blocks 31. Horizontal partitions, 32, 33, 34 and 35, divide the spaces in front and at the rear of flues 14 in such a manner that the 95 flues are divided into the five groups, designated a, b, c, d and e—each group comprising two separate flues—which are in communication through the spaces 36, 37, 38, 39 and 40 in such a manner that they form a 100 return-bend flue.

The open passages 41, 41' extending longitudinally of the recuperators permit the air to enter the flues 15, 15'. From 15, 15' the air divides into two currents in each 105 case, one passing to the producer, through the ducts 16, 16', while the main current passes through the port 42, into the riser flue 43, from which it passes through the passages 44, to the air nozzles 19. At this 110 stage of operations, the dampers 18, 18' on the air passages leading to the nozzles 19, 19'

2
are closed so that no air passes to the combustion flues. The kindling is now ignited, the fuel charging chute 20 being closed. The flame passes downward, igniting the coal or fuel in the bed, the combustion gases passing through the fuel bed to the ports 21 and 21', thence through the flues 22, 22' and 23, 23' to the riser flue 24. From 24, the producer gas enters the distributing flue 25, from whence it passes into the vertical flues 27 and 27' of the producer gas recuperators 3 and 3', respectively. Ascending through the flues 27 the gas passes around the horizontal flues 28^a, 28^b into the gas collecting-flue 45. From 45 the gases pass through the port 46, into the gas riser-flue 47, thence through the flue 48 to the gas downcomer-flue 49. From 49 it passes through the ports 50¹, 50², 50³, 50⁴, 50⁵ and 20 50⁶ to the several combustion flues 5¹, 5², 5³, etc. The gas entering the ports 21', on the other side of the oven setting, passes through the flues of this side, which correspond with the passages just described above, to the 25 combustion flues 6¹, 6², 6³, etc.

At first the gases leaving the producer are composed principally of products of complete combustion. As the coal becomes ignited however, and combustion penetrates 30 through the fuel bed the character of the gas changes and it gradually assumes the composition of ordinary producer gas. When the gas has become sufficiently rich to burn freely, the hand-holes 51 giving access 35 to the combustion flues 5¹, 5², etc., and nozzles 19 are opened in turn, and the gas flowing from the ports 50¹, 50², 50³, 50⁴, 50⁵ and 50⁶ ignited by the insertion of a torch or any suitable means. After the gas has been ignited 40 at each port, the damper 18 on the air nozzle 19 co-operating with that port is opened and the combustion, which is initially supported by the air entering through the hand-hole is now sustained by the air entering 45 through the nozzle. The combustion gases sweep through the flues 5¹, 5², 5³, 5⁴, etc., and thence pass downward through the passage 52 which is left at the end of the combustion flue space of the oven by stopping 50 the partitions 53¹, 53², etc., short of the front wall, 54, of the oven setting. As shown, these partitions are of unequal length, the length decreasing in the case of each partition from the upper to the lower one. There is thus provided, in effect, a flue of stepped cross-section, the cross-section increasing in proportion to the volume of gases flowing through the flue. The combustion gases pass through 52 into the horizontal flue 55. From 55 the gases pass in three streams. The first passes through the port 56, thence down through the duct 57 to the induction chamber of the injector 17. A damper, 67, regulates the combustion gas 60 passing to the duct 57. This first stream mixes with the air from the duct 16 and the commingled current passes through the injector into the gas producer chamber 2 and thence through the fuel bed. The CO₂ of this portion of the flue gas is reduced by the glowing fuel by the reaction, CO₂+C=2CO. This is an endothermic reaction, taking up heat from the fuel bed and so keeping down its temperature. The second stream of the combustion gases from 55, 70 passes into the passage 58, and thence through the flues 28^a, 28^b and connecting passage 59 of the producer-gas recuperator 3 into the flue 60 and thence to the connecting passage 39 of the air recuperator 4. A 75 damper, 61, on 58 serves to regulate the flow of combustion gases to the producer gas recuperator. The third stream of combustion gases passes through the length of 55 and thence into the passage 36 from which it 80 flows through the flues 14^a to the return-bend space 37, forward through 14^b, through 38 and thence back through 14^c into 39. Here, as already stated, it mingles with the combustion gases from 3 and the united current passes through 14^d to 40 and thence 85 back through 14^e and 62 to the main smoke flue, 63. A damper, 64, regulates the flow of the flue gases through 62. By the proper manipulation of damper 64 in conjunction with dampers 61 and 65 any desired distribution of the flue gases between the producer gas and air recuperators may be secured. After the fuel bed has been thoroughly ignited and the bed has been drawn 90 down by the removal of part of the ash on the grate, the damper 12 is slightly opened. A small portion of the air entering the passage 10 now passes through the duct 66 to the ash-pit of the producer chamber 2, 100 thence up through the ash on the grate, taking up heat from the lower layers and burning any residual carbon that has passed unconsumed into the ash bed. By this device the grate is protected against any injuriously high temperature, and the heat carried out of the fuel bed in the ash is recuperated. 105

When normal operating conditions have been established, air from blower 7 is passing to the recuperators 4 and 4'. A small portion of this air passes to the ash pit and upward through the lower part of the fuel bed therein, the major portion passing through the recuperator, in which it is 110 heated by the hot products of combustion passing through the flues 14, then dividing, in the case of each recuperator, into two streams, one, the primary current, going to the producer, the other, the secondary current, going to the combustion flues of the oven. The gas from the producer 2 passes through the producer gas recuperators 3, 3', where its temperature is raised by the hot 115 products of combustion passing through the 120

duct 16. The air from the recuperators 4 and 4' passes through the producer gas recuperators 3, 3', where its temperature is raised by the hot products of combustion passing through the 125

duct 16. The air from the recuperators 4 and 4' passes through the producer gas recuperators 3, 3', where its temperature is raised by the hot products of combustion passing through the 130

flues 28. From the recuperator the gas flows to the ports 50 of each side of the setting, thence into the combustion flues, where it is burned by the superheated air from the air nozzles. 5 The hot combustion gases, after passing through the combustion flues and yielding up part of their heat to the charge in the oven 1, divide into three streams—one going to the producer, one to the producer gas recuperator and one to the air recuperator. It 10 is to be noted that the three streams are withdrawn from the combustion flues and introduced into the three parts of the apparatus at the maximum permissible temperature. 15 This permits of the raising of both the producer gas and air to nearly the temperature of the products of combustion discharging from the combustion flues.

Having described my invention, what I 20 claim is:—

1. The process of heating which comprises, passing a mixture of preheated air and combustion gases downwardly through a bed of ignited carbonaceous material to 25 generate combustible gas, heating said combustible gas, burning the heated combustible gas with a second portion of preheated air, transferring heat from the gases resulting from said combustion to further portions 30 of air and combustible gas to heat the same, and passing a regulated volume of air upwardly through the burned fuel in the lower part of the said fuel bed to support the combustion of residual carbonaceous material in said burnt fuel.

2. The process of heating which comprises heating air under pressure in a recuperator by a stream of combustion gases, discharging one portion of the heated air under pressure above the ignited fuel bed of a gas producer in such manner as to induct into and mingle with said heated air a second stream of combustion gases, passing the said mixture of heated air and combustion gases 45 downward into said fuel bed to generate combustible gas, heating said combustible gas by a third stream of hot combustion gases, adding the said third stream of combustion gases to the said first stream, conducting 50 the heated combustible gas to a combustion space, conducting a further portion of said heated air to said combustion space and burning said gas by said air in said space to generate heat, and using the gaseous products of said combustion to heat fresh portions 55 of air and gas as above.

3. The process of heating which comprises heating air under pressure in a recuperator by a stream of combustion gases, discharging one portion of the heated air under pressure above the ignited fuel bed of a gas producer in such manner as to induct into and mingle with said heated air a second stream of combustion gases, passing the said mixture of heated air and combustion gases

downward into said fuel bed to generate combustible gas, heating said combustible gas by a third stream of hot combustion gases, mingling the said third stream of combustion gases with the said first stream at 70 that level in said recuperator at which the two streams have approximately the same temperature, conducting the heated combustible gas to a combustion space, conducting a further portion of said heated air into 75 said combustion space to generate heat, and using the gaseous products of said combustion to heat fresh portions of air and gas as above.

4. The process of heating coke ovens and the like which comprises dividing the current of combustion gases discharging from the heating flues of said apparatus into three streams, passing one of these streams of combustion gases through a recuperator 80 to heat a current of air, dividing the so-heated air current into two streams, discharging one of said streams of heated air through the nozzle of an inductor in such manner as to induct into and mingle with 85 said stream of heated air the second of said streams of combustion gases, passing the commingled air and combustion gases into a bed of ignited carbonaceous material to generate combustible gas, conducting the said 90 combustible gas through a gas recuperator, conducting the third stream of said combustion gases through said gas recuperator to raise the temperature of said combustible gas, discharging the second of said streams 95 of heated air into the combustion flues of 100 said apparatus in such manner as to induct the heated combustible gas into said flues, whereby the said combustible gas is burned by the air of said second stream, conducting 105 the said third stream of combustion gases after the same have passed through said gas recuperator to said air recuperator, and uniting the said third stream with said first stream of combustion gases in said air recuperator at that level therein at which the 110 temperatures of the respective currents are approximately equal.

5. The process of heating coke ovens and the like which comprises, dividing the current of combustion gases discharging from the heating flues of said apparatus into three streams, introducing a current of air under pressure greater than atmospheric pressure into an air recuperator, passing the 115 first of said streams of combustion gases through said air recuperator to heat the said air, dividing the heated air into two streams, conducting one of these air streams and the second of said streams of combustion gases 120 into a gas producer above the ignited fuel bed thereof, passing the commingled air and combustion gases downwardly through the said ignited fuel to burn said fuel and to generate producer gas, withdrawing the so- 125 130

formed producer gas from the lower part of said fuel bed but above the ash zone thereof, introducing a regulated volume of air into said gas producer below the ash zone thereof and passing said air upward into the said ash zone to burn residual carbon in the ashes in said zone, uniting the resulting gaseous streams, passing the united gaseous streams through a gas recuperator, 5 passing the third of said streams of combustion gas through said gas recuperator to raise the temperature of the said producer gas therein, conducting the heated producer gas to the combustion flues of said apparatus, conducting the second of said streams of heated air to said combustion flues, and discharging the said air thereinto in such manner as to induct the said producer gas into and mingle the same with said stream 10 of heated air in said combustion flues, whereby the said producer gas is burned therein, conducting the said third stream of combustion gases after the said gases have passed through said gas recuperator to said air recuperator and uniting the said third stream with the said first stream of combustion gases at that level in said air recuperator at which the said streams have approximately the same temperature.

15 6. The process of heating coke ovens and the like which comprises, dividing the current of combustion gases discharging from the heating flues of said apparatus into three streams, introducing a current of air under a pressure greater than atmospheric pressure into an air recuperator, passing the first of said streams of combustion gases through said air recuperator to heat the said air, mixing one portion of the heated air with the second of said streams of combustion gases, passing the resulting gaseous mixture through a bed of ignited fuel to burn said fuel and to generate combustible 20 gas, passing the so-generated combustible gas through a gas recuperator, passing the third of said streams of combustion gases through said gas recuperator to heat said combustible gas, conducting another portion of heated air to the combustion flues of said apparatus, discharging said heated air into said flues in a plurality of jets in such manner as to induct the said combustible gas into said flues and mingle the same with 25 said air, whereby the said gas is burned in said flues, conducting the third of said streams of combustion gases, after the same have been utilized in heating the said combustible gas to said air recuperator, and uniting the said first and third streams of combustion gases at that level in said air recuperator at which the temperatures of the two streams are approximately equal.

30 7. The process of heating coke ovens or like apparatus which comprises, dividing the combustion gases discharging from the combustion flues of said apparatus into three streams, passing air under pressure through an air recuperator, passing one of said streams of combustion gases through said air recuperator to heat said current of air, conducting a regulated portion of the so-heated air to a gas producer, discharging the heated air into said gas producer in such 35 manner as to induct thereinto the said second stream of combustion gases, the volume and pressure of the air so discharged being regulated to induct into said gas producer the quantity of combustion gases required to 40 give with said air a draft current so balanced with respect to the exothermic action of the air and the endothermic action of said combustion gases that the temperature of the fuel bed in said gas producer will be 45

into said flues and mingle with said air the said combustible gas, whereby said combustible gas is burned in said flues, conducting the said third stream of combustion gases, after said gases have passed through said 70 gas recuperator to said air recuperator and uniting the said third stream with the said first stream of combustion gases at that level in said air recuperator at which the said streams have approximately the same temperature. 75

8. The process of heating coke ovens and like apparatus, which comprises, dividing the combustion gases discharging from the heating flues of said apparatus into three 80 streams, introducing a current of air under a pressure greater than atmospheric pressure into an air recuperator, passing the first of said streams of combustion gases through said air recuperator to heat the said 85 air, mixing one portion of the heated air with the second of said streams of combustion gases, passing the resulting gaseous mixture through a bed of ignited fuel to burn said fuel and to generate combustible 90 gas, passing the so-generated combustible gas through a gas recuperator, passing the third of said streams of combustion gases through said gas recuperator to heat said 95 combustible gas, conducting another portion of heated air to the combustion flues of said apparatus, discharging said heated air into said flues in a plurality of jets in such 100 manner as to induct the said combustible gas into said flues and mingle the same with said air, whereby the said gas is burned in said flues, conducting the third of said streams of combustion gases, after the same have been utilized in heating the said combustible gas to said air recuperator, and uniting the said first and third streams of combustion gases at that level in said air recuperator at which the temperatures of the two streams are approximately equal. 105

9. The process of heating coke ovens or like apparatus which comprises, dividing the combustion gases discharging from the combustion flues of said apparatus into three streams, passing air under pressure through an air recuperator, passing one of said streams of combustion gases through said air recuperator to heat said current of air, conducting a regulated portion of the so-heated air to a gas producer, discharging the heated air into said gas producer in such 110 manner as to induct thereinto the said second stream of combustion gases, the volume and pressure of the air so discharged being regulated to induct into said gas producer the quantity of combustion gases required to 115 give with said air a draft current so balanced with respect to the exothermic action of the air and the endothermic action of said combustion gases that the temperature of the fuel bed in said gas producer will be 120 125 130

- maintained at a point below the clinkering temperature of the ash, passing the said draft current downward through the ignited fuel bed of said gas producer to burn 5 said fuel and to generate combustible gas, passing a current of air upward through the ash zone of said fuel bed to burn out any residual carbon therein, withdrawing the said combustible gas and the gases resulting 10 from the reaction of said second current of air with said residual carbon from a level in said fuel bed just above the ash zone thereof, passing the combustible gas current through a gas recuperator, passing the third 15 stream of said combustion gases through said gas recuperator to heat said combustible gas, conducting the so-heated combustible gas to the combustion flues of said apparatus and burning the same therein by 20 means of the remainder of said heated air.
9. The process of heating coke ovens or like apparatus, which comprises passing a mixed draft current of air and combustion gases in regulated proportions downward 25 through a bed of ignited carbonaceous material to burn said material and to generate combustible gas, the relative proportions of air and combustion gas in said draft current being so regulated with respect to the exo- 30 thermic reaction of the oxygen of the air and the endothermic reaction of the carbon dioxide of said combustion gases with the carbon of said carbonaceous material that the temperature of said fuel bed will be 35 maintained below the clinkering point of the ash of said carbonaceous material, passing a draft current of air upward into the ash zone of said fuel bed, to burn residual carbon in the ashes in said zone, withdrawing 40 the combustible gases resulting from the contact of the said draft currents with the carbon of said fuel bed and accompanying incombustible gases from an intermediate
- level of said fuel bed, conducting the gases withdrawn from said fuel bed to the combustion flues of said apparatus, conducting air to said combustion flues, and burning said gas by said air in said flues to heat said apparatus. 45
10. The process of heating coke ovens and 50 the like which comprises passing a mixed draft current of air and combustion gases downward into the ignited fuel bed of a gas producer, the depth of said fuel bed, the volume of said draft current and the 55 time of contact of the said draft current therewith being so regulated that oxygen and carbon dioxide of said draft current react with the carbon of said fuel to form carbon monoxide, the relative proportions of 60 air and combustion gases in said draft current being so regulated with respect to the exothermic reaction of the oxygen and the endothermic reaction of the carbon dioxide with the carbon of said fuel bed that the 65 temperature thereof will be maintained below the clinkering temperature of the ash of said fuel, passing a draft current of air of limited volume upward into the ash zone of said fuel bed to burn residual carbon in 70 the ash in said zone, withdrawing from said fuel bed at an intermediate level thereof the gases formed in said bed and unchanged gases introduced into said bed, conducting the gases withdrawn to the combustion flues 75 of said apparatus, conducting air to said flues and burning the combustible matter of said gas by said air to heat said apparatus. 70

Signed at New York city in the county of New York and State of New York this 16th 80 day of January A. D. 1911.
